DANIEL A. HAAS, OF BELLEVILLE, ILLINOIS.

SHOCKER ATTACHMENT FOR BINDERS.

1,272,426.

Specification of Letters Patent.

Patented July 16, 1918.

Application filed June 28, 1917. Serial No. 177,608.

To all whom it may concern:

Be it known that I, DANIEL A. HAAS, a citizen of the United States, residing at Belleville, in the county of St. Clair and State of Illinois, have invented certain new and useful Improvements in Shocker Attachments for Binders, of which the following is a specification.

This invention relates to shocker attachments for binders, and has for its primary object to provide a shocker of simplified and improved construction which is capable of being readily applied to or detached from binders of that type now in use.

15 A further object of the invention is to provide a shocker of the character mentioned which normally remains in position to receive a bundle or shock, but which may be quickly and easily actuated to dump the 20 bundle and after performing this function, the said shocker automatically returns to normal or bundle-receiving position.

Still further objects reside in providing a shocker of the type mentioned, which is 25 composed of but few readily assembled parts, which has its various parts so assembled as to minimize the opportunity for wear or breakage, which derives its operating power from the power mechanism upon 30 the binder, and which will prove thoroughly efficient in practice.

With these objects in view together with others which will appear as the description proceeds, the invention resides in the novel 35 formation, combination and arrangement of parts all as will be described more fully hereinafter, illustrated in the drawings and particularly pointed out in the claims.

In the drawings:

40 Figure 1 is a top plan view of a shocker attachment constructed in accordance with the invention, and illustrating the parts in the position they will assume under normal conditions,

45 Fig. 2 is an end view of the device illustrated in Fig. 1,

Fig. 3 is a side elevation of the improved shocker,

Fig. 4 is a longitudinal sectional view 50 taken through a portion of the shocker bar,

Fig. 5 is an end elevation of the rotatable member which is employed for operating the shocker bar, and

Fig. 6 is a sectional view taken through 55 the housing for the rotatable member, and

illustrating the mechanism for throwing the shocker bar into operation.

In carrying out the invention, use is made of a frame of relatively small dimension which is applied to the binder adjacent the 60 bull or power wheel thereof. This frame is indicated generally at 5, and includes a pair of spaced parallel bars 6 and 7, rigidly secured to the end bars 8, the latter being secured at their inner ends to the frame or 65 body of the binder. This improved frame also includes a supporting bar or rod 9, disposed in spaced parallel relation to the bars 6 and 7, but projecting outwardly beyond the body or frame of the binder.

70 Mounted for rotation in a suitable bearing 10 secured between the bars 6 and 7 intermediate the ends of the latter, is a jack shaft 11, to one end of which is secured a sprocket wheel 12, over which passes a chain 75 13. This chain in turn passes over a sprocket 14 upon the binder, and which may be driven in any suitable manner from the power wheel, or from a power mechanism located upon the binder. The outer end of 80 the shaft 11 is equipped with a disk 15, which will be referred to hereinafter as the rotatable member. This disk is housed within a casing 16, the latter being secured in any preferred manner to the frame 5, and 85 it will be observed that the outer end of this casing is open. The disk 15 is provided in its periphery with spaced teeth indicated at 17, which teeth are adapted to engage and deliver a rotary and oscillatory 90 movement to the shocker bar to be herein-after detailed.

95 The shocker bar is indicated generally at 18, and is pivoted intermediate its ends as at 19, to the supporting bar or rod 9. The outer end of this shocker bar carries a shock holder indicated generally at 20, and within which the bundles are adapted to be dropped. This shock holder may be of any approved construction, and when the shocker 100 bar is in normal position, this holder is disposed so as to receive and support a bundle or shock delivered thereto from above. The bar 18 may be hollow throughout its entire length, and a pin 21 is slidably arranged 105 within the inner end of said bar, being held against rotary movement therein by a tie bolt or pin 22, and the said pin also serves to limit the longitudinal sliding movement of the shaft pin 21. The outer extremity 110

of the pin 21 is equipped with a head 23, the latter extending within the disk inclosing casing 16. It will be observed that the open end of the casing 16 is provided with 5 an inwardly extending flange 24, behind which the head 23 engages, and it is obvious from this construction that the pin will be prevented from becoming disengaged from the interior of the housing. The casing 16 10 is offset as at 25, so that when the pin 21 is disposed within the offset portion, the said pin will be out of the course of travel of the teeth 17 upon the periphery of the disk or rotatable member 15. It is obvious, therefore, 15 that when the shocker bar is in such position that the pin 21 carried thereby will be disposed within the offset portion, rotary movement of the disk 15 can in no way affect the said shocker bar. A guide plate 40 20 is arranged in the housing in the path of travel of roller 23, so as to cause the latter to move into the offset 25 once in each revolution of the arm.

Arranged within the annular wall of the 25 casing 16 and adjacent the offset portion 25 thereof is a movable leaf 26, which is adapted when moved inwardly to engage with the pin 21 and to force the same out of the offset portion and into the path of travel 30 of the teeth in the periphery of the disk 15. Said leaf is hinged as shown, and a lever 27 operated by a rod or cord 28 is adapted to rock the said leaf into operative position. A suitable spring may be employed for returning these parts to normal position after 35 pressure upon the rod or cord 28 has been released.

Rigidly secured to the shocker bar 18 and adjacent the inner end thereof is an arm 29. 40 This arm extends downwardly as shown, and is connected at its free end with the frame 5 by a link or rod 30. It is apparent from this construction that rotary movement delivered to the inner end of the shocker rod or bar will be limited, and as the disk 15 rotates, the said bar will be partially rotated 45 and operated. To permit of this peculiar movement of the shocker bar, the pivot arrangement of the shocker bar consists of a pair of clevises 31 and 32, pivoted together as shown, the former of which is connected loosely to the shocker bar, while the latter is secured to the bar or rod 9. It will be 50 observed that the first mentioned of these clevises is disposed between a pair of collars 55 33 affixed to the shocker bar.

As has been before stated, when the shocker bar has its inner end disposed within the offset portion of the casing 16, the shock 60 received at the outer end of the bar is disposed with its tines or teeth substantially parallel to the ground, so as to retain a shock or bundle delivered thereto. When it is desired to deposit this bundle, the cord 65 or rod 28 is pulled, whereupon the bell-

crank lever 27 depresses the leaf 26, thus forcing the inner end of the shocker rod downwardly into the path of travel of the teeth on the disk 15. One of the said teeth thereupon engages the pin 21, and carries 70 the latter around the casing. This movement of the inner end of the shocker rod causes the outer end of the said rod first to move rearwardly and then downwardly, and as the inner end of the said bar continues 75 to move, the link or rod 30 secured to the arm 29 will limit the rotation of the said shocker bar, and after the inner end of the said bar reaches the lowermost extent of its movement and starts traveling upwardly, 80 the said bar will rotate, so that the shock holder will be inverted. This part oscillatory and part rotary movement of the shocker bar causes the holder at the outer end thereof to become inverted, and as the 85 binder passes over the ground, the teeth or tines of the said holder will pass over the upper end of the shock which has been deposited upon the ground. As soon as the inner end of the shocker bar again enters the 90 offset portion, the shock holder at the outer end thereof will have resumed normal position, and is ready to receive more bundles or shocks.

From the foregoing, it will be obvious 95 that I have provided an extremely simple and yet thoroughly efficient shocker attachment for use upon binders, and one in which the mechanical operations are performed automatically after once the mechanism has 100 been set into operation.

While the present is a disclosure of the preferred embodiment of the invention, it is to be understood that the invention is not limited thereto, as various changes in the 105 minor details of construction, proportion, and arrangement of parts may be resorted to if desired without departing from the spirit of the invention as defined by the appended claims.

What is claimed is:

1. In a device of the class described; a power mechanism having a rotatable member, a shocker bar pivoted intermediate its ends and being capable of oscillating, a 115 shock holder carried by said bar, and means for establishing a connection between one end of said bar and said rotatable member.
2. In a device of the class described; a power mechanism having a rotatable member, teeth on said member, an integral shocker bar throughout its entire length capable of swinging and oscillatory movement, a shock holder on said bar, and means for moving one end of said bar into the 125 path of travel of said teeth.
3. In a device of the class described; a rotatable member, a shocker bar pivoted inwardly from one end and being capable of oscillating, an arm on one end of said bar, 130

a link connected to the outer end of said arm for limiting the movement of the latter, and means for connecting the said end of said bar with said rotatable member.

- 5 4. In a device of the class described; a frame, a rotatable member on said frame, a shocker bar pivoted intermediate its ends to said frame and being capable of swinging and oscillatory movement, an arm secured to the said bar adjacent the inner end of the latter, a link connecting said arm and frame, and the inner end of said bar being adapted to be engaged with and carried by said rotatable member.
- 10 5. In a device of the class described; a frame, a rotatable member on said frame, a shocker bar pivoted inwardly from one end to said frame and being capable of swinging and oscillatory movement, a sliding member in said bar adapted to be engaged by and carried with said rotatable member, an arm secured to said bar, a link connecting said arm and said frame, and means for moving said bar so that said sliding member will be engaged by said rotatable member.
- 15 6. In a device of the class described; a frame, a drum, the said drum being provided with an offset portion, a rotatable member in said drum, teeth on said rotatable member, a shocker bar, the said shocker
- 20
- 25
- 30

bar having one end disposed within said casing, the said end being adapted normally to lie within said offset portion, a leaf pivoted in said casing, a lever upon the exterior of said casing adapted when rocked in one direction to depress said leaf to move said shocker bar into the path of travel of said teeth, means for rocking said lever, and a shocker on the outer end of said shocker bar.

7. In a device of the class described; a power mechanism, a shocker bar capable of swinging and oscillating, a shock holder on said bar, a rotatable member in said power mechanism, a housing for said rotatable member having an offset at one side thereof, the said shocker bar extending into said housing, teeth on said rotatable member adapted to engage the inner end of said shocker bar, and a deflecting plate in said housing adjacent said offset portion and in the path of travel of said shocker bar for causing the latter to move out of engagement with said teeth and into said offset portion.

In testimony whereof I affix my signature in presence of two witnesses.

DANIEL A. HAAS.
